UNITED STATES PATENT OFFICE.

SAMUEL M. GREENIDGE, OF WASHINGTON, DISTRICT OF COLUMBIA.

AUTOMATIC MECHANISM FOR RAISING LIQUIDS.

Application filed December 24, 1921. Serial No. 524,602.

To all whom it may concern:

Be it known that I, SAMUEL M. GREENIDGE, a citizen of the United States, and resident of Washington, in the District of Columbia, have invented certain new and useful Improvements in Automatic Mechanism for Raising Liquids, of which the following is a full, clear, and exact description.

My invention relates to a new and improved mechanism for automatically ejecting oil, water, or other liquids, from a well, and one of the objects of my invention is to provide a mechanism of this character which, though automatically ejecting oil or water

from a well at intervals depending on the rapidity with which oil or water accumulates in the well, yet has only a very few moving parts, and is of the utmost simplicity in construction.

Another object of the invention is to provide an automatic ejecting means of this character which may be operated either by an artificial pressure introduced into the well, or by the natural pressure of gas in the well or surrounding strata; the shifting from natural to artificial pressure, or vice versa, requiring only a slight modification in the arrangement of the pressure supply pipe.

Another advantage of my invention resides in so arranging the mechanism that the float controlling the mechanism in accordance with the level of the oil or water in the well, may be located either below or above the mechanism, as the conditions of the particular well may demand.

Another object of the invention is to provide a simple means by which the ejecting mechanism may be maintained in operative position for a sufficient time to insure the oil or water being completely ejected from the ejection pipe.

Other and further objects of my invention will appear as the description proceeds.

I will now describe a particular form of my invention, it being understood that those skilled in the art may make many changes and modifications therein without departing from the spirit of the invention as defined in the appended claims, and the drawings forming part of this specification are therefore to be considered merely as illustrative, and not in any limiting sense.

In the drawings:

Figure 1 is a vertical sectional view of the

well casing, pipes, and operating mechanism; the float being shown in elevation, and there being a break between the top and bottom portion of the well.

Figure 2 is an enlarged elevation of the mechanism; the well casing and guard being in section.

Figure 3 is a vertical sectional view through the mechanism, taken at right angles to the view shown in Figure 1; the well casing being omitted.

Figure 4 is a detail sectional view showing the lower valve in closed position.

Figure 5 is an enlarged horizontal sectional view taken on line 5—5 of Figure 1. 70

Figure 6 is an enlarged horizontal sectional view taken on line 6—6 of Figure 1; the well casing being omitted.

Figure 7 is an enlarged horizontal sectional view taken on line 7—7 of Figure 1; 75 the well casing being omitted.

Figure 8 is an enlarged horizontal sectional view taken on line 8—8 of Figure 1; the well casing being omitted.

Figure 9 is an enlarged horizontal sectional view taken on line 9—9 of Figure 1; 80 the well casing being omitted.

Figure 10 is a vertical sectional view of a modified form of the apparatus; the float, guard, and well casing being omitted; and,

Figure 11 is a detail view showing one arrangement of the pressure supply pipe when the ejecting mechanism is being operated by natural pressure.

Referring to the drawings more in detail, 90 numeral 1 indicates the ordinary well casing, which in the present instance is closed at the top by packing referred to by numeral 2. This packing is preferably of rubber.

Passing down into the well are two pipes, 95 3 and 4; pipe 3 being hereafter referred to as the pressure supply pipe; and pipe 4 being hereafter referred to as the ejection pipe. Adjacent the bottom of the well these pipes 3 and 4 are connected with a body 100 member 5, which body member is preferably a single piece casting and is provided with certain passages, valves, etc., to be later described. Another pipe 6 is attached to the body member adjacent the bottom thereof, 105 and in the particular embodiment illustrated, a float 7 is adapted to ride on this pipe, its position, of course, being controlled by the level of the oil, water, or other liquid in the well. It will be obvious that it is not essen- 110

tial that the float be mounted on the pipe, as any other arrangement would produce the desired result.

The pressure supply pipe 3 communicates with a passage 8 in the body member, and this passage communicates, through a valve 9, with another passage 10 leading to the eduction pipe 4. Opening into the pressure supply passage 8 is another passage 11 leading through a valve 12 to the bottom of a cylinder 13. Mounted in the cylinder 13 is a piston 14 carrying the piston rod 15.

A link 16 (Figures 2 and 3) connects the float 7 with an operating arm 17 of the cylinder valve 12, and the arrangement is such that when the float has been raised to a certain point by accumulation of oil or water, the cylinder valve 12 will be moved to open position as shown in Figure 1. Pressure is thus admitted to the bottom of cylinder 13, and the piston and piston rod are raised. Another link 18 connects the piston rod 15 with the valve 9, and the arrangement is such that as the piston rod is raised the valve 9 is moved to open position so that communication is opened between the pressure supply passage 8 and the eduction passage 10; and also between the oil or water supply pipe 6 and the eduction passage 10. In order to function in the manner described, the valve 9 is provided with two passages 19 and 20; the passage 19 communicating with the pressure supply passage and the eduction passage when the valve is open; and the passage 20 communicating with the oil or water supply pipe 6 and the eduction passage 10 when the valve is open. When the valve is moved to closed position communication is cut off between the pressure supply passage and the eduction passage, and also between the oil or water supply pipe and the eduction passage, as clearly shown in Figure 4.

The operation of the apparatus thus far described is as follows:

As the oil or water accumulates the float will rise, and through the link connection 16 the cylinder valve 12 will be moved to open position and pressure will be admitted to cylinder 13 through the passage 11. The admission of pressure to the cylinder will cause the piston and piston rod to rise, and the link connection between the piston rod and the valve 9, will cause the latter to be moved to open position as shown in Figure 1. The fluid pressure in the passage 8 will now pass through passage 19 into the eduction passage 10 and will lift the oil or water through the pipe 6 and eject it through the eduction pipe 4. The oil or water will be rapidly ejected and the float will fall, thereby closing the cylinder valve 12 and thus cutting off the pressure supply to the cylinder.

It will be apparent that if the ejecting fluid pressure is admitted to the eduction

passage only momentarily it might happen that the oil or water would not be lifted all the way to the top of the well and hence would fall back in the eduction pipe when the ejecting pressure was cut off. It is therefore highly desirable that some means be provided to insure the ejecting pressure being applied for a sufficient period to entirely clear the eduction pipe. For this purpose I have provided the following means.

A by-pass 21 communicates with the top and bottom of the cylinder, and the size of the by-pass passage is adjusted by any desirable means, such as a screw plug 22. Now when pressure to the cylinder is cut off, the spring 23 will slowly force the piston downwardly, the fluid passing from the bottom of the cylinder through the by-pass and back into the cylinder above the piston. As the piston slowly descends the valve 9 will be moved to its closed position and the fluid pressure to the eduction passage will be cut off. At the next cycle of operation when pressure is admitted to the bottom of the cylinder the pressure above the piston will be permitted to escape through the one-way valve 24. To permit access to the one-way valve 24, an aperture is provided in the wall of the body member, the wall of the aperture being screw-threaded and receiving a plug 25.

The time required for the piston to descend, and hence the time of closing the valve 9, is adjusted by the adjustment of the size of the by-pass passage by means of the adjusting screw 22. It will be apparent from the foregoing description that the closing of the valve 9 is entirely independent of the float.

It may be desirable to protect the mechanism from injury, particularly when lowering it into the well, and for that purpose I have provided a guard member 26, which is shown as entirely surrounding the mechanism and being closed at the top and bottom. Apertures 27 are provided in the bottom of the guard to permit the oil or water to reach the float, and at the same time preventing sand or other solid material from reaching the mechanism and interfering with its proper function. The particular form of the guard member does not constitute any essential part of the invention, and it may be entirely open at the bottom or top, or both; or it may be entirely omitted if preferred.

It is to be noted that the float 7 could be arranged above the casting 5 if the conditions of certain wells demanded such an arrangement. Obviously it is only necessary to place a float of the proper construction above the casting and connect it with the operating arm 17 of the valve 12 by means of the link 16. The operation of the mechanism would remain exactly the same.

In Figure 10 I have shown a slightly modified form of the mechanism; the main difference being that a reciprocating valve is substituted for the rotary valve 9. The pressure supply passage 8, eduction passage 10, passage 11, cylinder valve 12, and the mechanism for operating said valve, cylinder 13, piston 14, by-pass 21, one-way valve 24, oil or water supply pipe 6, and various other elements, remain the same as previously described and no further description thereof is necessary. In this construction, however, the piston rod 15 extends downwardly and is connected with a reciprocating double valve 28. A spring 29 exerts pressure on the valve 28 to normally hold it in its lowered position. When the float is raised by the accumulation of oil or water, the cylinder valve 12 will be opened in the manner previously described, thus admitting pressure to the cylinder and raising the piston 14. As the piston rod rises it lifts the double valve 28 and permits direct communication between the pressure supply passage 8 and the eduction passage 10, and also between the oil or water supply pipe 6 and the eduction passage 10, as clearly shown in Figure 10. When the oil or water is ejected and the float drops back the supply of pressure to the cylinder will be cut off by the valve 12; and the spring 29 will force the piston and double valve slowly downward, its movement being retarded in the previously described manner by means of the by-pass 21. When the valve reaches its lowermost position it cuts off communication between the pressure supply passage and the eduction passage; and also between the oil or water supply pipe and the eduction passage, as will be obvious from an inspection of Figure 10.

In the foregoing description it has been assumed that sufficient artificial pressure would be supplied to the pressure supply pipe to operate the mechanism and to eject the oil, water, or other liquid. But in many localities there is sufficient natural gas pressure in the well or surrounding strata to operate the mechanism and eject the liquid, and in accordance with my invention, this natural pressure may be employed in the same manner as with the use of artificial pressure. One arrangement adapted for use in connection with natural pressure is indicated in Figure 11. In this arrangement the upper portion of the pressure supply pipe is dispensed with, and the remaining section of this pipe is closed at the top by a plug 30, or other closure. The section of pipe 3 remaining must be of sufficient length to extend a short distance above the highest level to which oil or other liquid will rise in the well. Apertures 31 are provided in the section 3, adjacent the top thereof, whereby the natural gas under pressure in the well may

enter pipe 3 and operate the mechanism in the manner previously described in connection with the use of artificial pressure. In place of using the shortened pipe section 3 as shown in Figure 11, the same result may be accomplished by simply closing the pressure supply pipe 3 at the top of the well, and by providing suitable apertures in this pipe at a point above the highest level to which the oil or water will rise in the well.

When natural gas pressure is used for operating the mechanism, only such small amounts of it will be used as are necessary to eject the oil or other liquid from the well during the time valves are open, and the natural gas will thereby be conserved for use in other processes such as lighting or heating.

When the mechanism is to be operated by artificial pressure, such as compressed air, there will be no necessity for the closing of the passage 20 in valve 9, Figure 1, or of using the lower portion of the double valve 28, Figure 10. The omission of these parts would thereby simplify the construction of the mechanism and still further simplify or reduce the number of moving and wearing parts.

In the use of artificial pressure, such as compressed air, for the operation of the mechanism, there will usually be more or less water in the pressure supply passage due to condensation; but this will not interfere with the proper working of the mechanism, as obviously liquid pressure admitted to the cylinder 13 would operate the mechanism in the same manner as when gas pressure is admitted thereto.

It will be understood that the relative arrangement of the pressure supply passage, the eduction passage, and the valve system, is merely a matter of choice and they may be arranged in any desired relative positions to increase the compactness of the mechanism.

In accordance with the patent statutes I have described what I now believe to be the best embodiments of my invention, but I do not wish to be understood thereby as limiting myself or the scope of my invention, as many modifications may be made without departing from the spirit of my invention, and all such I aim to include in the scope of the appended claims.

What I claim as new and desire to secure by Letters Patent is:

1. An automatic mechanism for raising liquids from a well, including a pressure supply pipe, an eduction pipe, and a liquid supply pipe, a valve for controlling communication between the three pipes, and means for controlling said valve in accordance with the level of the liquid in the well.

2. An automatic mechanism for raising liquids from a well, including a body mem-

ber provided with a pressure supply passage, an eduction passage, and a liquid supply inlet, a valve for controlling communication between the pressure supply passage, the 5 eduction passage, and the liquid supply inlet, and means for controlling the operation of said valve in accordance with the level of the liquid in the well.

3. An automatic mechanism for raising 10 liquid from a well, including a pressure supply passage, an eduction passage, a valve for controlling communication between the said passages, means for operating said valve in accordance with the level of the liquid in 15 the well, and means for retarding the closing of said valve.

4. An automatic mechanism for raising liquid from a well, including a body member provided with a pressure supply passage, 20 an eduction passage, and a liquid supply inlet, a rotary valve for controlling communication between the pressure supply passage, the eduction passage and the liquid supply inlet, and means controlled by the 25 level of the liquid in the well for rotating said valve to open position.

5. An automatic mechanism for raising liquid from a well, including a body member provided with a pressure supply passage, 30 an eduction passage, and a liquid supply inlet, a rotary valve for controlling communication between the pressure supply passage, the eduction passage and the liquid supply inlet, means controlled by the level 35 of the liquid in the well for rotating said valve to open position, and means for retarding the closing of said valve.

6. An automatic mechanism for raising liquid from a well, including a pressure 40 supply passage, an eduction passage, and a liquid supply inlet, a rotary valve for controlling communication between the said passages and inlet, said valve being provided with two passages so arranged that one passage 45 will communicate with the pressure supply passage and the eduction passage when the valve is open, and the other will communicate with the liquid supply inlet and the eduction passage when the valve is open.

50 7. An automatic mechanism for raising liquid from a well, including a pressure supply passage, an eduction passage, and a liquid supply inlet, a rotary valve for controlling communication between the said passages and inlet, said valve being provided with two passages so arranged that one passage 55 will communicate with the pressure supply passage and the eduction passage when the valve is open, and the other will communicate with the liquid supply inlet and the eduction passage when the valve is open, and means controlled by the level of the liquid in the well for rotating said valve to open position.

60 8. An automatic mechanism for raising

liquid from a well, including a pressure supply passage, and an eduction passage, a valve for controlling communication between said passages, a cylinder and piston, a passage leading from the pressure supply 70 passage to the bottom of said cylinder, a second valve for controlling said passage, a float, a connection between said float and said second valve to open the valve and admit pressure to the cylinder when the float 75 rises, and a connection between the piston and the first mentioned valve, whereby the first mentioned valve is opened when the piston is raised.

9. An automatic mechanism for raising 80 liquid from a well, including a pressure supply passage, and an eduction passage, a valve for controlling communication between said passages, a cylinder and piston, a passage leading from the pressure supply 85 passage to the bottom of said cylinder, a second valve for controlling said passage, a float, a connection between said float and said second valve to open the valve and admit pressure to the cylinder when the float 90 rises, a connection between the piston and the first mentioned valve, whereby the first mentioned valve is opened when the cylinder 95 is raised, and a by-pass from the bottom of said cylinder for controlling the descent of the piston.

10. An automatic mechanism for raising liquid from a well, including a pressure supply passage, and an eduction passage, 100 a valve for controlling communication between said passages, a cylinder and piston, a second valve for controlling the admission of pressure to said cylinder, a float connected with and operating said second valve in accordance with the level of the liquid in the well, a connection between the said piston and the first mentioned valve, whereby said first mentioned valve is opened by movement of the piston, and means for retarding the descent of said piston. 110

11. An automatic mechanism for raising liquid from a well, including a pressure supply passage and an education passage, a valve for controlling communication between 115 said passages, a cylinder and piston, a second valve for controlling the admission of pressure to said cylinder, a float connected with and operating said second valve in accordance with the level of the liquid in the well, a connection between the said piston and the first mentioned valve, whereby said first mentioned valve is opened when the piston 120 is raised, and an adjustable by-pass for retarding the closing of the first mentioned valve. 125

12. An automatic mechanism for raising liquid from a well, including a pressure supply passage and an eduction passage, a valve for controlling communication between said 130 passages, and means for opening and clos-

ing said valve, said means being controlled by the level of the liquid in the well for opening the valve, and being operable to close the valve after the liquid has fallen 5 to a predetermined level.

13. An automatic mechanism for raising liquid from a well, including an eduction 10 passage and a liquid supply passage, a valve for controlling communication between said passages, and means for opening and closing said valve, said means being controlled by the level of the liquid in the well for opening said valve, and being operable to close the valve after the liquid has fallen 15 to a predetermined level.

14. An automatic mechanism for raising liquid from a well, including a pressure supply passage, an eduction passage, a liquid

supply passage, and a valve for controlling communication between said three passages, 20 and means for opening and closing said valve, said means being controlled by the levels of the liquid in the well for opening said valve, and being operable to close the valve after the liquid has fallen to a pre- 25 determined level.

15. An automatic mechanism for raising liquid from a well, including a body member, said body member being provided with a pressure supply passage and an eduction 30 passage, a valve for controlling communication between said passages, a float for opening said valve, and a guard member surrounding said body member and float.

SAMUEL M. GREENIDGE.
